GARDEN TOOL

Richard O. Bartz, 7017 Mark Terrace Drive,
Edina, Minn. 55435

Filed Apr. 25, 1973, Ser. No. 354,326

Term of patent 14 years

Int. Cl. D8—99

U.S. Cl. D8—9

FIG. 1

FIG. 2

FIG. 3

FIG. 4

FIG. 5

FIG. 6

FIG. 7

FIG. 8

FIG. 1 is a side elevational view of a garden tool of my new design. The opposite side of the garden tool is a mirror image of FIG. 1;

FIG. 2 is a bottom plan view of the garden tool of FIG. 1;

FIG. 3 is a top plan view of the garden tool of FIG. 1;

FIG. 4 is an enlarged sectional view taken along the line 4—4 of FIG. 1;

FIG. 5 is an enlarged front elevational view of the blade end of the garden tool of FIG. 1;

FIG. 6 is an enlarged elevational view of the handle end of the garden tool of FIG. 1;

FIG. 7 is an enlarged sectional view taken along the line 7—7 of FIG. 1; and

FIG. 8 is an enlarged sectional view taken along the line 8—8 of FIG. 1.

I claim:

The ornamental design for a garden tool, substantially as shown and described.
